UNITED STATES PATENT OFFICE

160,248

ROTATABLE ARTICLE DISPLAY DEVICE
OR THE LIKERobert B. Clime, Seattle, Wash., assignor to Joseph M. Aiken, Seattle, Wash.

Application October 22, 1949, Serial No. 5,647

Term of patent 7 years

(Cl. D80—9)

To all whom it may concern:

Be it known that I, Robert B. Clime, a citizen of the United States of America, residing at Seattle, King County, in the State of Washington, have invented a new, original, and ornamental Design for a Rotatable Article Display Device or the like, of which the following is a specification, reference being had to the accompanying drawing, forming part thereof.

The figure is a top perspective view of my novel rotatable article display device or the like.

The display device is symmetrical about the vertical plane in which its axis of rotation lies and is symmetrical about a median vertical plane perpendicular to its axis of rotation.

I claim:

The ornamental design for a rotatable article display device or the like, substantially as shown and described.

ROBERT B. CLIME.
